APPARATUS FOR COATING PIPES

Carl K. Smith, 133 Gibson Lane, Corpus Christi, Tex.

Filed Apr. 25, 1960, Ser. No. 24,481

2 Claims. (Cl. 25—38)

This invention relates to the coating of pipe and more particularly to apparatus for applying to the external surface of metal pipes a protective and weighting coating.

In the application of protective and weight increasing coatings to pipes, as heretofore commonly practiced, it has been customary to apply such coatings by spraying or impelling the coating material against the external surface of the pipe while simultaneously moving the pipe longitudinally past the coating apparatus and rotating the pipe. Coatings of various kinds, such as asphalt and concrete, have been successfully applied in this manner to metal pipes for the purpose of protecting such pipe from corrosion and weighting the same to prevent the pipe from floating when installed beneath water or in marshy ground. Ordinarily, pipe for such use is first coated with a corrosion resistant coating, such as asphalt and is thereafter covered with a thick layer of heavy concrete containing suitable weighting material, such as barite or other heavy aggregate material.

The treatment of pipe in this manner requires the use of two separate coating operations involving costly machinery and the exercise of close control over the operations which greatly adds to the labor and expense and increases the expenditure of time.

When a protective coating, such as asphalt, is employed, it is usually applied in a liquid condition, so that it becomes necessary to allow the coating to set or harden, or to employ other means of preventing the disruption of the coating during subsequent treatment or handling. The application of heavy concrete to pipe is carried out while the concrete is in an unset condition and of relatively soft consistency such that the coating is easily scraped off or broken, so that careful handling and storage of the coated pipe becomes necessary to allow setting and proper hardening of the coating before the pipe can be safely transported.

The present invention has for an important object the provision of apparatus for the coating of pipe, whereby a protective and weight increasing coating, having greatly improved durability, may be applied to the pipe in a single pass of the pipe through the machine.

Another object of the invention is to provide apparatus for coating pipe embodying the application to the pipe of a combined corrosion resistant and weight imparting coating, whereby the use of multiple coats is avoided and a coating of improved hardness, durability and resistance is obtained.

A further object of the invention is the provision of pipe coating apparatus by which a hard, durable and corrosion resistant coating may be applied and compacted upon the external surface of pipe, and which enables the pipe to be immediately handled without danger of injury to the coating.

Another object of the invention is to provide coating applying apparatus having means for moving a pipe longitudinally therethrough and including means for applying a relatively dense and substantially non-flowing coating material to be the exterior of the pipe and extruding the coating material in contact with the pipe as the pipe moves through the machine to compact the coating on the pipe to form thereon a dense and durable coating.

A further object of the invention is the provision in a pipe coating machine of the kind referred to of means for supporting lengths of pipe in end to end axial alignment for substantially continuous movement through the ma-

2

chine and including means for rapidly conveying away the individual lengths of pipe after they have been coated.

Another object of the invention is to provide conveyor mechanism for use with pipe coating apparatus of the type mentioned by which lengths of pipe may be quickly assembled in end-to-end axial alignment and moved longitudinally at a constant rate through the machine and including means for maintaining the lengths of pipe in axial alignment during coating of the same and for quickly and easily conveying away each length as soon as it has been coated.

A further object of the invention is the provision of coating apparatus for pipes comprising a stationary part positioned to surround a pipe and through which the pipe may be moved longitudinally, a rotatably mounted part positioned in surrounding relation to the pipe and shaped to act upon a coating material applied to the exterior of the pipe to propel the material longitudinally with the pipe and means on the stationary part positioned to be engaged by the material to compact the material against the pipe as the pipe and material move through the parts.

The above and other important objects and advantages of the invention may best be understood from the following detailed description, constituting a specification of the same, when considered in conjunction with the annexed drawings, wherein—

FIGURES 1 to 4, inclusive, are side elevational views on a reduced scale showing the overall arrangement of the pipe coating apparatus of the invention and illustrating various stages of the method by which the coating operation is carried out;

FIGURE 5 is a plan view, partly broken away and partly in cross-section of the coating material feeding and compacting mechanism of the invention;

FIGURE 6 is a cross-sectional view, taken along the line 6—6 of FIGURE 5, looking in the direction indicated by the arrows;

FIGURE 7 is a side elevational view of the coating feeding and applying mechanism, as shown in FIGURE 5;

FIGURE 8 is a cross-sectional view taken along the line 8—8 of FIGURE 5, looking in the direction indicated by the arrows;

FIGURE 9 is a cross-sectional view, taken along the line 9—9 of FIGURE 5, looking in the direction indicated by the arrows;

FIGURE 10 is a cross-sectional view, taken along the line 10—10 of FIGURE 7, looking in the direction indicated by the arrows;

FIGURE 11 is a perspective view, on a somewhat enlarged scale, of the rotatable feeding and compacting member of the invention;

FIGURE 12 is a side elevational view, partly in cross-section, of the pipe propelling mechanism of the invention;

FIGURE 13 is a cross-sectional view, taken along the line 13—13 of FIGURE 12, looking in the direction indicated by the arrows;

FIGURE 14 is a cross-sectional view, taken along the line 14—14 of FIGURE 12, looking in the direction of the arrows;

FIGURE 15 is a side elevational view, partly in cross-section, showing the pipe supporting and feeding mechanism of the invention;

FIGURE 16 is a side elevational view of one of the pipe supporting carriages of the pipe conveying mechanism by which the coated pipe is carried away from the coating applying mechanism;

FIGURE 17 is a front end elevational view of the pipe supporting carriage of FIGURE 16, as seen from the left side of FIGURE 16;

FIGURE 18 is a fragmentary perspective view of the

conveyor mechanism of the invention showing cable winding mechanism used therewith;

FIGURE 19 is a front elevational view, partly broken away and on a somewhat enlarged scale, showing details of structure of the cable winding mechanism of FIGURE 18;

FIGURE 20 is a cross-sectional view, taken along the line 20—20 of FIGURE 5, looking in the direction indicated by the arrows; and

FIGURE 21 is a fragmentary perspective view, on a somewhat enlarged scale, illustrating a portion of the reinforcing wire winding mechanism as seen in FIGURE 20 and showing details of structure thereof.

Referring now to the drawings in greater detail, the invention is disclosed herein in connection with its use in the coating of pipes, such as the steel pipes used in the construction of pipelines, which are buried in the ground and particularly the coating of such pipes with a durable and relatively hard coating of protective and weighting material, for example, a material made up of about 75% of an aggregate consisting of sand and gravel comminuted shell, or the like, 25% hydraulic cement, 7% asphalt and 5% water. Such a composition contains relatively little water and is substantially non-flowing, so that it is unsuitable for application to the pipe without compressing or compacting the material on the external surface of the pipe.

It will be understood, of course, that the example given above is intended merely for the purpose of illustration and that substantial modification of the composition, both as to the character of the ingredients used and the proportions of the same, may be employed by the use of the method of the invention and the apparatus thereof to accomplish the purposes of the invention. A composition of this character, when applied to a pipe by the method of the invention, provides a protective and weight imparting coating of greatly improved durability and hardness, while at the same time the coating possesses sufficient flexibility to permit transportation and handling of the pipe without cracking or disintegration of the coating. A coating of this kind also possesses the advantage that its hardness increases substantially with age, so that the coating eventually attains a hardness approaching that of concrete.

The apparatus of the invention includes a supporting structure or bed, which may conveniently be made up of sectional frames, 10, of rectangular construction adapted to be positioned in endwise abutting engagement and secured together in any convenient manner, as by bolting or welding, to form an elongated support upon which pairs of longitudinally spaced rollers 12 are rotatably mounted, in position to support sections of pipe P for longitudinal movement along the bed.

Each of the pairs of rollers may be mounted on a common shaft 14, extending laterally of the bed and mounted in suitable bearings attached to the bed, certain of the shafts being provided with sprockets 16, as best shown in FIGURE 15, about which drive chains 18 may pass for the purpose of rotating the rollers simultaneously to move the pipe along the bed. Suitable means may be provided, such as an electric motor 20, drivingly connected to a right angled drive 22, which is in turn connected to a drive chain 24, which passes over an additional sprocket 26 on one of the shafts 14, whereby the rollers 12 may be rotated at any desired speed to control the movement of the pipe along the bed.

At one end of the bed, an additional supporting frame 28 is positioned, through which the pipe P may move and which is provided with upper and lower sets 30 and 32 of longitudinally spaced pairs of rollers 34, similar to the pairs of rollers 12, the lower set 32 of the rollers 34 being vertically movable relative to the upper set 30, as by means of screw threaded rods 36 attached at their lower ends to the lower set and extending vertically upwardly through suitable openings in cross members of

the support frame 28, and provided with nuts 38, threaded on their upper ends, whereby the lower frame may be moved vertically to move the rollers 34 into clamping engagement with the pipe P.

Each pair of the rollers 34 is carried by a shaft 40 similar to the shafts 14, rotatably mounted in suitable bearings 42, and the shafts 40 are provided with sprockets 44 about which drive chains 46 extend, to cause the rollers to rotate simultaneously. Suitable means, such as electric motors 48 are provided, which operate through right angled drives 50 to actuate drive chains 52 which pass about additional sprockets 54 on certain of the shafts 40, whereby the rollers 34 are rotated. By this arrangement, the pipe P may be tightly engaged between the sets of rollers 34 and the speed of the rollers may be regulated to feed the pipe P through the feeding mechanism at any desired speed.

In operating the pipe supporting and longitudinally feeding mechanism of the invention, the sections of pipe P may be assembled on the bed on the rollers 12 and suitably connected together, as by means of tapered plugs 56, to hold the pipe sections in horizontal alignment. The rollers 12 may then be operated by the motor 20 to extend the pipe through the feeding mechanism, whereupon the rollers 34 may be clampingly engaged with the pipe by actuation of the nuts 38, so that the driving rollers 34 may be operated by the motors 48 to feed the pipe at any desired rate. It will be apparent that by operating the supporting rollers 12, at a speed somewhat greater than the speed of the feeding rollers 34, the sections of pipe may be maintained in abutting relation, so that a continuous string of pipe may be moved into the feeding mechanism, the rollers 12 being capable of slipping relative to the pipe to hold the sections against becoming separated during the feeding of the pipe through the apparatus.

The coating applying mechanism of the invention, indicated at 60, in FIGURES 1 to 4, is located beyond the outlet end of the pipe feeding mechanism, and is supported on suitable framework of generally rectangular construction, which may include ground contacting skids 62, by which the coating mechanism as a unit may be readily moved about to properly position it in longitudinal alignment with the pipe supporting bed and feeding mechanism. The frame of the coating applying mechanism includes upright frame members 64, which may be suitably tied together at their upper ends, as by means of a top plate 66, or otherwise. Vertically positioned plates 68 and 70 are attached to the inner faces of the upright 64, as by means of bolts 72 extending through vertically elongated slots 74 in the plates, and provided with nuts 76, whereby the plates may be adjusted vertically to the uprights. The plates extend beyond the uprights at one side of the coating mechanism, to provide spaced apart flanged portions 78, serving as supports for certain parts of the coating mechanism, to be more particularly described hereinafter.

The plates 68 and 70 have central, circular openings 69 and 71 therethrough, as best seen in FIGURE 9, and circular headers 80 and 82 are carried by the plates and provided with central openings 81 and 83 therethrough which are in registration with the openings of the plates. The headers 80 and 82 may be attached to the plate by means of bolts 84, extending through the plates and headers and provided with nuts 86. The openings 81 and 83 of the headers form circular trackways within which the opposite ends of a tubular driving element 88 extend, suitable roller bearings, such as those indicated at 90, as shown in FIGURE 9, being positioned between the ends of the element 88 and the trackways 81 and 83 to allow the element to rotate freely in the headers.

The header 80 also carries adjustable rollers 92, carried by radially adjustable frames 94, slidably attached to the header by means of certain of the bolts 84 to allow the rollers to be adjusted radially into engagement with

the external surface of the pipe P to center the pipe in the coating mechanism. The rotatably mounted, tubular driving element 88 is provided with sprocket teeth 96 about its external periphery, as shown in FIGURES 7 and 9, about which drive chains 98 extend, by which the element 88 is rotated.

As best seen in FIGURE 9, one end of the driving element 88 is internally threaded to receive a material compacting sleeve 100, which is carried by the driving element for rotation therewith and extends longitudinally beyond the header 82. The material compacting sleeve 100 is shown on an enlarged scale in FIGURE 11, and is formed with an external annular flange 102, mediate its ends and is cut away at one end to form helically or angularly shaped end faces 104 and lateral notches 106, which are preferably semi-circular in shape. The end faces 104 form pressure faces which are positioned to engage the coating material and coat therewith to move the coating material longitudinally in contact with the external surface of the pipe upon rotation of the compacting sleeve as the pipe moves longitudinally through the coating mechanism. An external confining sleeve 108 is provided, surrounding the outer end portion of the compacting sleeve 104, which confining sleeve is carried by a support plate 110, having openings through which the bolts 84 pass upon which nuts 112 are threaded, to hold the confining sleeve centralized about the compacting sleeve. The confining sleeve may be attached to the support plate by radially extending gussets 114. The confining sleeve 108 has an internally restricted portion 116 near its outer end, through which the coating material is extruded by the longitudinal force exerted thereon by the pressure faces 104 of the compacting sleeve and the movement of the pipe through the coating mechanism to firmly compact the coating on the external surface of the pipe. The confining sleeve 108 has a lateral opening 118 through which an inlet pipe 120 opens into the interior of the confining sleeve, and within which a feed screw 122 is rotatably mounted on a shaft 124, by which the coating material is fed into the interior of the confining sleeve. The inlet pipe 120 has an upwardly extending branch pipe 126, through which coating material is supplied to the inlet pipe from any suitable source, such as a hopper, not shown.

The rotation of the compacting sleeve 100 and the material feeding screw 122 is accomplished by suitable driving mechanism which may include an electric motor 128 which, in the present illustration, drives a countershaft 130, operatively connected to a countershaft 132 as by means of a driving chain 134, the countershaft 132 being drivingly connected to the shaft 136 of a right angled drive 138, as by means of a drive chain 140. The right angled drive 138 in turn rotates an upper countershaft 142, which carries a sprocket 144, drivingly connected by a drive chain 146 to a sprocket 148 on the shaft 124 of the screw 122, whereby the screw is rotated.

The countershaft 132 also carries sprockets 150, mediate its ends about which the chains 98 operate, which chains pass about the external sprocket teeth 96 of the driving element 88 with which the compacting sleeve 100 is rotatable.

Suitable clutch mechanism, not shown, may be provided on the countershaft 130, positioned to be operated by clutch rod mechanism 152, connected to a lever 154, pivotally mounted on the top plate 66, whereby the operation of the material feeding and compacting mechanism may be stopped and started at any desired time.

Additional clutch means, not shown, may also be provided, suitably connected to the driving mechanism which connects the upper countershaft 142 to the material feeding screw 122, which clutch mechanism may have an operating rod 188, connected to a lever 160, pivotally mounted on the top plate 160 adjacent the lever 154, whereby the operation of the material feeding mechanism may be started or stopped independently of the

material compacting mechanism, when desired. It will be appreciated that the clutch mechanism by which the driving of the material feeding and compacting mechanisms are controlled may be of any conventional design, and that these clutch means may be operated in any suitable manner convenient for the purpose.

The drive chain 140 may be provided with a guard 164, suitably attached to the shafts 142 and 124.

Outwardly beyond the outer end of the confining sleeve 108, an additional vertically disposed plate 166 is supported on additional uprights 168, similar to the uprights 64, the plate being adjustable vertically in the same manner as the plates 68 and 70, previously described, which plate has a central opening 170, about which a tubular extension 172 extends, whose free end is positioned close to the outer end of the confining sleeve 108, the opening 170 being in axial alignment with the confining sleeve. Circumferentially spaced rollers 174 are rotatably supported on journals 176 on the plate 166 in surrounding relation to the opening 170, upon which rollers a gear ring 178 is supported in concentric relation to the opening for rotation on the rollers. The ring 178 is rotated by a drive chain 180, which passes about the ring and about the sprocket 182 carried on the shaft of an electric motor 184.

The ring 178 carries rotatably mounted spools 186 upon which reinforcing wire is wound and the ring also carries a wire guiding mechanism 188 for each of the spools, including rotatable pulleys 190, mounted on brackets, such as the bracket 192, shown in FIGURE 21, about which the wires 194 from the spools is fed, to wind the wires about the pipe P upon rotation of the ring 178, to imbed the wires in the coating. The wires 194 extend between the adjacent ends of the cylindrical extension 172 and confining sleeve 108 and may be anchored to the pipe in any suitable manner as by spot welding the ends of the wires to the pipe, so that upon rotation of the ring 178, the wires will be wound off of the spools 186 and imbedded in the coating on the pipe.

For the purpose of conveying away sections of the pipe to which the coating has been applied, conveyor mechanism is provided, such as that shown generally at the left hand of FIGURES 1 to 4, inclusive, and details of whose construction is illustrated in FIGURES 16 to 19, inclusive. The conveyor mechanism includes a track having rails 196, extending longitudinally beyond the discharge end of the coating applying mechanism and upon which pipe supporting carriages 198 and 200 are supported for rolling movement along the track. The carriage 198 is adapted to be moved longitudinally along the track by means of continuous cables 202 and 204, which are separately attached to opposite sides of this carriage and which extend about guide pulleys 206 located at the outer ends of the track and about separate portions 208 and 210 of an elongated winding drum 212, which is rotatably mounted adjacent the discharge end of the coating applying mechanism. The portions 208 and 210 of the winding drum are defined by pairs of longitudinally spaced annular flanges 214 on the drum, between each pair of which a wire 216 is spirally wound on the drum to form an external thread with which the cable is engageable to cause the cable to be wound spirally on the drum, as best seen in FIGURE 19. The ends of each cable may be suitably anchored to the drum as by means of U-bolts 218 and 220.

The drum is suitably supported for rotation on a shaft 222 rotatably mounted in suitable bearings, and which is provided with driving mechanism, which takes the form of an electric motor 224 located beyond one end of the shaft and connected in driving relation thereto, in any conventional manner, such as by the use of sprockets attached to the shaft 222 and to the shaft 226 of the motor and a drive chain which passes about the sprockets and which may be enclosed within a guard 228. The

motor 224 may be operated to rotate the drums in either direction and at any desired speed.

The other end of the shaft 222 is connected in driving relation to suitable brake mechanism, which may take the form of an electric motor 230, suitably connected in driving relation to the shaft as by means of enclosed chain drive mechanisms 232 and 234 of conventional design, which are connected together by means of a right angled drive 236. The brake mechanism is connected to the shaft in a manner to control and restrain the rotation of the shaft during the movement of the carriage 198 away from the coating applying mechanism and suitable automatic clutch mechanism of conventional design generally indicated at 238 is provided, whereby the brake is disconnected from the shaft 222 during the return movement of the carriage 198, to permit the carriage to be returned quickly.

The carriage 198 is provided with means for anchoring the end of a section of the pipe P to the carriage against rotational movement relative thereto, which anchoring means may conveniently take the form of an arcuate saddle 240 mounted on the carriage in position to receive the end of the pipe, as illustrated in FIGURES 16 and 17. The saddle may be lined with a suitable material, such as brick lining, shown at 242, upon which the pipe rests and the saddle also carries a releasable clamp 244 which may be positioned over the pipe to hold the pipe in tight engagement with the saddle. The clamp 244 has a releasable latch, provided with a lever 246, by which the clamp may be quickly tightened or released.

The carriage 200 is provided with a centrally positioned saddle 248, which is suitably mounted for vertical adjustment, to position the saddle in engagement with the coating on the pipe at any desired location, whereby a section of the pipe which has been coated may be supported on the carriages 198 and 200 in a substantially horizontal position for movement along the track to a desired storage location.

In the operation of the invention, constructed and arranged as described above, sections of the pipe P are positioned on the pipe supporting mechanism, resting upon the rollers 12 thereof and are connected together in axial abutting relation by inserting the tapered plugs 56 into the ends of the sections, the rollers 12 being rotated to move the connected sections along the bed toward the pipe feeding mechanism at a rate slightly in excess of the rate at which the pipe moves through the feeding mechanism to prevent the sections from becoming separated.

The continuous length of pipe, thus provided, is moved into the pipe feeding mechanism and the rollers 34 brought into frictional contact with the pipe by tightening the nuts 38. The rollers 34 are then rotated by operation of the electric motors 48 to propel the pipe through the pipe coating mechanism.

The foremost one of the pipe sections is extended by the pipe feeding mechanism into the pipe coating mechanism until an uncoated portion, of suitable length, of the front end of the section is extended beyond the confining sleeve 108, after which the coating applying mechanism is actuated to rotate the compacting sleeve 100 while feeding the coating material against the external surface of the pipe by means of the feed screw 122. During the feeding of the coating material and the rotation of the compacting sleeve 100, the feeding material will pass through the openings or notches 106 of the compacting sleeve into contact with the external surface of the pipe, and the coating material will be compacted and moved in the same direction as the pipe by the pressure faces 104 of the compacting sleeve. As the material is thus fed into the coating apparatus and acted upon by the compacting sleeve, the pipe will be moved forwardly to carry the coating material with it into the restricted portion 116 of the confining sleeve 108, so that under the influence of the movement of the pipe

and the compacting force exerted on the material by the compacting sleeve, the material will be strongly compacted against the pipe and extruded through the restricted portion 116 to compress the material on the pipe. By providing a coating material of suitable consistency, the material will be solidly compacted on the pipe to form a relatively hard and durable coating C of a character to permit handling of the pipe and storage of the same without disintegration or other injury to the coating.

As the pipe moves out of the coating applying mechanism, the uncoated front end portion F of the pipe will be moved into a position to rest upon the saddle 240 of the carriage 198, the carriage 200 being then beneath the coated portion of the pipe. The uncoated end portion F is then clamped on the saddle 240 by tightening the clamp 244, and the carriage 198 is moved forwardly by operation of the electric motor 224 to rotate the winding drum under the restraining influence of the braking mechanism, which may be adjusted to regulate the movement of the pipe through the coating applying mechanism at a rate to assure the uniform application of the coating to the pipe.

When a section of pipe has been thus coated for a substantial part of its length, the saddle 248 of the carriage 200 is elevated to engage the coating to support the pipe in a substantially horizontal position in axial alignment with subsequent sections of pipe in the apparatus, and as soon as the coating on one section has been completed, the coating applying mechanism is stopped and the pipe is further moved through the apparatus to leave a second uncoated end portion on the section, as will be clearly seen in FIGURE 3. The thus completely coated section of pipe is then moved away from the coating applying mechanism by operation of the carriage 198, the pipe being supported in a horizontal position by the carriages 198 and 200 to convey the pipe to a storage location. When the coated section has been thus moved to storage, the carriage 198 is quickly returned, bringing with it the carriage 200, to position the carriages to receive the next section of pipe.

By repeating the above operations, it will be apparent that sections of pipe may be coated in quick succession and moved to storage with a minimum of expense and labor. During the coating operation, the feeding of the coating material may be stopped at any desired point by actuation of the lever 160, so that the pipe may be moved through the apparatus without the application thereto of the coating, whereby the end portions of the pipe may be readily left in an uncoated condition.

It will also be apparent that the wires 194 may, if desired, be wound about the coating to become imbedded therein during the coating of the pipe by actuation of the winding mechanism, as illustrated in FIGURES 5, 20 and 21.

In the event that it should be desired to provide a coating of different thickness to the pipe or to coat a pipe of different outside diameter, this can be accomplished by removing the confining sleeve 108 and the compacting sleeve 100 and replacing these elements with others of suitable size.

It will thus be seen that the invention, constructed and operated as described above, provides inexpensive apparatus of simple design and rugged construction.

The invention is disclosed herein in connection with certain specific structures and arrangements of parts, but it will be understood that these are intended by way of illustration only and that numerous changes can be made in the construction and arrangement of the parts, within the spirit of the invention and the scope of the appended claims.

Having thus clearly shown and described the invention, what is claimed as new and desired to secure by Letters Patent is—

1. Pipe coating apparatus comprising means for sup-

porting a pipe for movement along a longitudinal axis, a tubular member mounted for rotation about said axis and through which the pipe may move, means for supplying a coating material to the external surface of the pipe at a location mediate the ends of the member as the pipe moves through the member, means on the member positioned for engagement with the material on the pipe to move the material with the pipe, a tubular element surrounding the member and through which the pipe may move in concentric relation to the element and formed with an internally restricted portion shaped for engagement with the material on the pipe to compress the material against the pipe.

2. Pipe coating apparatus comprising means for supporting a pipe for movement along a longitudinal axis, a tubular confining element surrounding the axis and through which the pipe may move in radially inwardly spaced, concentric relation to the element, means for applying a coating material to the external surface of the pipe in the element, a tubular member mounted for rota-

tional movement about the pipe between the pipe and element and having a portion shaped for engagement with the material to move the material longitudinally with the pipe, said element having an internally restricted portion positioned for engagement with the material on the pipe as the pipe moves through the element to compress the material against the pipe.
